(57) **CLAIM**

The ornamental design for a cap for medication bottle, as shown and described.

DESCRIPTION

FIG. 1 is a front elevational view of a cap for medication bottle showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is an exploded front elevational view thereof, revealing a rotatable ring;

FIG. 9 is a right side elevational view thereof;

FIG. 10 is a rear elevational view thereof;

FIG. 11 is a left side elevational view thereof; and,

FIG. 12 is a perspective view thereof.

In the drawings, the evenly-spaced broken lines showing portions of a cap depict environment and form no part of the claim; the dash-dot-dash lines represent boundaries of the claimed design and form no part thereof.
